UNITED STATES PATENT OFFICE.

HUGH C. LIGGETT, ROY PETERSON, AND SHERMAN W. LIGGETT, OF SALINEVILLE, OHIO.

MINE-DOOR-OPERATING MECHANISM.

Application filed May 27, 1922. Serial No. 546,022.

To all whom it may concern:

Be it known that we, HUGH C. LIGGETT, ROY PETERSON, and SHERMAN W. LIGGETT, citizens of the United States, residing at 5 Salineville, in the county of Columbiana and State of Ohio, have invented certain new and useful Improvements in Mine-Door-Operating Mechanisms, of which the following is a specification, reference being 10 had to the accompanying drawings.

This invention relates to mine doors, and particularly to means for automatically operating the mine doors upon the approach of a trip of cars in either direction.

15 The general object of this invention is to provide a very simple, effective and safe mechanism of this character including a solenoid operatively connected to the doors to shift them from a closed to an open position, the doors being provided with means whereby they are closed after the solenoid is de-energized, and switches disposed in such position that they may be engaged by the trolley of an approaching car and 20 turned to energize the solenoid as the car approaches the door, or turned to de-energize the solenoid after the car or trip of cars have passed through the door.

25 A further object is to provide means whereby the doors may be opened and closed in case the current is cut off.

Another object is to provide a construction of this kind which does not electrify the rails and which is not, therefore, likely 30 to become grounded.

Still another object is to provide a construction of this kind which is capable of being used either with a single or double door.

40 Other objects will appear in the course of the following description.

My invention is illustrated in the accompanying drawings, wherein:—

45 Figure 1 is a top plan view of a mine track with our improved mine door and operating mechanism associated therewith;

Figure 2 is an elevation of the door and part of the operating mechanism, the rails being in section;

Figure 3 is a sectional view through one of the switches;

Figure 4 is an elevation of the lower corner of the door and shaft 15;

Figure 5 is a diagrammatic view of the electrical circuit and the two switches in one position, showing the circuit broken through the solenoid a battery being shown as the means for producing current;

Figure 6 is a like view to Figure 5 but showing the switches closed to close the circuit through the solenoid, this view also showing a preferable manner of energizing the solenoid by connecting one of the switches to the trolley wire;

Referring to these drawings, 10 designates the rails of a mine track and 11 a rectangular door frame which arches over these rails and which is shown as extending at an acute angle thereto, though it may be disposed at any other angle. Hingedly mounted upon the door frame are the doors 12. These doors are provided with hinge leaves 13 and the door frames with hinge leaves 14 which are attached to a vertical shaft 15, one for each door, the lower end 70 of each vertical shaft being mounted in a suitable bearing 16. The lower end of each shaft 15 carries a sector gear 17, these gears facing in the same direction, and coacting with these sector gears is a longitudinally 75 extending rod 18 which has rack teeth 19 adapted to engage with the two sector gears 17 and which forms part of or is connected to the core of a solenoid 20. A spring 21 urges the door operating rack rod 18 in a 80 direction to close the doors, while upon the solenoid being energized the rack rod will shift in the opposite direction to open the doors.

For the purpose of energizing the solenoid automatically upon the approach of a car to the doorway and de-energizing the solenoid after the car or the train has passed through the doorway, we provide the two-way switches 22 and 23 disposed on opposite sides of the door and adjacent the trolley wire 24. The two-way switches are constructed in any usual or suitable manner,

ordinary commercial switches being used for this purpose, but the stem 25 of each switch carries at its outer end a multi-bladed actuating member 26. This has four radial blades and each blade is slotted, as at 27, to embrace and straddle the trolley wire 24. One of the wires of the solenoid 20 is connected to the switch 23, another wire extends to the railway rail, and another wire extends from switch 22 to the trolley wire. The circuits between these two-way switches 22 and 23 are of ordinary type and so arranged that when the trolley of the car moving in a direction from right to left strikes one of the actuating members 26, it will rotate it in a direction to turn on the current and connect the solenoid with the source of current. This energizes the solenoid and causes the doors to open. The car then passes through the doorway and eventually its trolley strikes the actuating member 26 of the switch 23 and turns this actuating member, which cuts off the current. Immediately that the solenoid is de-energized, the spring 21 causes the rack bars to move in an opposite direction and the doors to close, and it does not matter in which direction the car approaches it will energize the solenoid at a proper point to open the doors and de-energize the solenoid after it has passed through the doors.

Preferably each door 12 has attached to it the outwardly projecting, somewhat curved extension 28. These extensions, as illustrated in Figure 1, are curved so as to extend nearly parallel to the track when the doors are opened and being for the purpose of preventing the door from becoming wrecked if the power should happen to go off with a train of cars going through the door. These strips under these circumstances will come in contact with the train of cars and keep the doors open until the train of cars have entirely passed through the doorway.

In Figure 5 we have illustrated diagrammatically the solenoid 20 as being connected in a normally interrupted circuit with a battery, such as a storage battery, but preferably the power for actuating the solenoid 20 will be taken from the cable 24, as illustrated diagrammatically in Figure 6, as where a storage battery is used the battery must be renewed at relatively short intervals or two batteries must be used so that when one is out of condition the other may be connected in circuit.

It is to be particularly noted with regard to this mechanism that it is very simple, that it does not use an electric motor of ordinary construction but a solenoid acting as a motor for the door, such a solenoid being much less expensive than a regular motor. Furthermore, it is very readily installed, has very simple bearings and connections, and

very little that can possibly get out of order. It will likewise be noted that the actuation of this door is not dependent upon the use of a track rail. Where a track rail is used as part of a circuit for operating the electric door opening mechanism, it must be insulated from adjoining rails and insulated from the ground, and it often happens that a mule has to drag the cars and in this case the mule would be likely to come in contact with the rail and would receive a shock, which would either cause the mule to run away, or if the current was of sufficient voltage, would kill the mule. Furthermore, it is extremely difficult to properly insulate a rail of this construction. With our construction there is no insulated rail and nothing which carries the current which by any chance could come in contact with a mule or with a person.

Of course, we may use either a single door or a double door without any departure from the spirit of the invention.

While we have illustrated a construction which is very simple and thoroughly effective, obviously we do not wish to be limited to the details illustrated, as these details might be varied in many ways without departing from the principle of the invention as defined in the appended claims.

We claim:

1. The combination with a mine door, of a track extending through the doorway and a trolley wire above the track, of means for swinging the door to an open position automatically upon the approach of a car in the other direction including a solenoid disposed in a normally open circuit with a source of energy, a core for the solenoid and connected to a rack, a sector gear operatively connected to the pivotal axis of the door and actuating said rack, means normally urging the rack in a direction to hold the door closed, the energizing of the solenoid causing the shifting of the rack to open the door, switches disposed one on each side of the door and connected in circuit with the source of energy and the solenoid and adapted to alternately close and open said circuit, and switch actuated members disposed adjacent the trolley wire and adapted to be engaged by the trolley wheel of the car.

2. In combination with a mine door, of a track extending through the doorway and a trolley wire above the track and extending through the doorway, of means for swinging the door to an open position automatically upon the approach of a car in either direction including a solenoid disposed in a normally open circuit with the trolley wire and with one of the track rails, a core for the solenoid connected to a rack, a sector gear operatively connected to the pivotal axis of the door and operating said rack, means normally urging the rack in a direction to

hold the door closed, the energizing of the solenoid causing the shifting of the rack to open the door, switches disposed one on each side of the door and disposed in circuit between the solenoid and the trolley wire, each of said switches being adapted to alternately close and open said circuit, and switch actuating members disposed adjacent the trolley

wire and adapted to be engaged by the trolley wheel of the car. 10

In testimony whereof we hereunto affix our signatures.

HUGH C. LIGGETT.
